UNITED STATES PATENT OFFICE

LEWIS B. DOMAN, OF SYRACUSE, NEW YORK

AUTOMATIC PIPE ORGAN

Application filed January 12, 1926. Serial No. 80,747.

This invention relates to an automatic pipe organ involving the use of one or more manual key-boards commonly known as "manuals" and a pedal key-board usually termed "pedals" together with a system of "stops" for selectively playing any particular part or combination of parts of a musical composition as may be desired, without in any way interfering with the voluntary operation and control of the keys of either of the manuals or pedals or any one of the stops in the usual manner for playing the same or any other musical composition.

This instrument contemplates the use of two sixty-one note manuals, a thirty note pedal action and sixty stops, making a total of two hundred and twelve different elements to be either voluntarily or automatically operated, one of the manuals being designated as the "accompaniment" manual and the other as the "solo" manual, and the main object of my present invention is to provide simple and efficient means whereby all of these elements may be automatically operated and controlled by a relatively narrow music sheet and a correspondingly short tracker bar having a maximum number of, in this instance, ninety-five rows of perforations and tracker ducts respectively, but it will be evident from the following description that other perforations and ducts for special purposes may be added, if desired.

In other words, it is assumed that a music sheet providing for sixty-one rows of note perforations and a corresponding number of tracker ducts, is sufficient for playing any composition for the organ, certain ones of which are adapted for playing "solo" parts, others for "accompaniment" parts and still others for "pedal" parts, the remaining thirty-four rows of perforations and tracker ducts being used in the selection and operation of certain solo divisions of the manuals and pedals and also in the selection and operation of the "stops", "switches" and "canceling" devices hereinafter more fully described.

Another object is to provide means controlled by the note perforations and tracker ducts for selecting from the sixty-one notes, those or parts of those which are to be played

on the solo manuals or on the pedals and to utilize the same tracker ducts which select the solo parts for selecting the various stops on which the various parts are to be played.

A further object is to provide means whereby a limited number of pipes may be made to serve as several stops as for example, from a set of ninety-seven pipes may be derived five or more stops which are available for use on either of the manuals or pedals without interfering with their use in the same or any other pitch on any other manual or pedal at the same time, all of which enables the instrument to be built in a comparatively small space and at relatively low cost and at the same time, secures greatly increased resource in tonal capacity and avoids the inconveniences and difficulties arising from the use of relatively wide music sheets.

Other objects and uses relating to specific parts of the instrument will be brought out in the following description.

In the drawings:—

Figure 1 is a diagrammatic view, partly broken away, of the major parts of the "console" of the organ.

Figure 2 is an enlarged diagrammatic view, partly in section, of certain parts of the console for selecting and controlling solos and accompaniments on the "manuals", showing also portions of the "pipe chest", "contact box" and electro-pneumatic controlling means therefor of the organ.

Figure 3 is an enlarged diagrammatic view, partly in section, of certain parts of the console for selecting and controlling the "pedal solos" and including portions of the pipe chest, contact box and electro-pneumatic operating means therefor.

Figure 4 is a diagrammatic view, partly in section and partly broken away, of certain parts of the console and organ for selecting and controlling the operation of the various "stop-bars" and contact box therefor.

Figure 5 is a diagrammatic view of a music sheet showing a limited number of note perforations and their possible divisions and also showing limited number of additional rows of perforations for selecting and controlling the solo divisions of the manuals.

and pedals, and stops and additional rows of perforations for canceling previously selected solos and stops.

Figure 6 is an enlarged diagrammatic view of the electric switches of one of the contact boxes and the operating pneumatics for said switches showing the method of selectively switching the notes of any one division from accompaniment to solo and vice versa.

Figure 7 is a rear elevation, partly broken away of a portion of the contact box for supporting the diagonally disposed bristles used for accompaniment and solo playing showing the manner of connecting bristles representing like notes in the several stops throughout the five octave range of the organ.

The instrument as a whole, may be divided broadly into two general units, one unit comprising what may be termed the "organ parts" and the other unit the "console parts" with suitable connections by which the two units may be installed or placed in juxtaposition or any practicable distance apart either at the same or at different levels. The parts of either unit may be arranged in many different relations or, in some instances, certain parts of either unit may be incorporated in the other unit, as may be found to be most expedient, or may contribute to greater efficiency, and for this reason, as well as for clarity of description, both units are shown more or less diagrammatically.

The majority of the movable parts of both units are pneumatically operated and other parts of the same units are electrically operated to simplify the construction and to afford a wider range of relative installation of units but it is evident that many of the electrically operated parts may be operated pneumatically and vice versa within the scope of the invention.

Organ parts

The organ parts may include any number of sets of sound-producing pipes —A'— commonly known as "stops" which may be operatively connected to any number of wind chests as —1— each having a high-pressure air chamber —4— and a relatively lower-pressure air chamber —3— for sounding the pipes.

The wind chest —1— is preferably composed of an upper section —5— and a lower section —6—, said sections being detachably secured to each other by screws —7— to form the chamber —3— in which the playing pressure for the pipes may be maintained by any suitable means not shown, while the section —6— contains the chamber —4— in which a relatively high pressure is maintained by the same or any other means not necessary to herein illustrate or describe for the reason that any suitable device may be used for supplying air under pressure to either or both of said chambers.

The pipes of each set communicate with the corresponding chamber —3— through tubular ports —8—, one for each pipe, each port being extended into the chamber —3— for conducting air under pressure to the corresponding pipe.

The section —6— having a high pressure chamber —4— extends into the chamber —3— and is provided with a top wall —9— supported by posts —10— and having a plurality of pouches or diaphragms —11— each normally closing one of the ports —8— for preventing the passage of air from the chamber —3— to the corresponding pipe.

The upper wall of the high pressure chamber —4— forms the lower wall of the air chamber —3— and also supports the posts —10— so that the high pressure chamber —4— extends downwardly some distance below the air chamber —3— and is provided at its lower end with atmosphere chambers —12— each having opposed air ports —13— and —14— one set for each pipe, in vertically spaced relation controlled by an armature valve —15— of an electro-magnet —16—.

The port —13— is formed in the upper wall of the chamber —12— for connecting said chamber with the high pressure chamber —4— while the port —14— opens to the atmosphere, but is normally closed by the valve —15— acting under its own weight, and by air pressure from the chamber —4—.

A tube —17— extends through both of the chambers —4— and —3— and has its lower end connected to the chamber —12— and its upper end connected to the pouch —11— whereby the high pressure air, normally passing from the chamber —4— through the port —13— into the chamber —12— and thence through the tube —17— to the pouch —11—, serves to normally close the corresponding port —8—, it being understood that the lower wall of the high pressure chamber —4— is provided with a plurality of ports —13— and —14—, electro-magnets —16— and pipes —17— corresponding to the number of pouches —11— and pipes —A'—; that is, one of each of those parts for each pipe while the chamber —4— may be common to all of the ports —13— and —14—.

The pipe supporting section —5— carrying the relatively short tubes —8— is stationary while the section —6— and parts carried thereby including the diaphragm —11— may be removed from the section —5— and tubes —8— by downward displacement by simply removing the screws —7— to permit inspection or repairs of the enclosed parts without disturbing the pipes.

The distance between the lower end of the section —5— and lower ends of the tubes —8— is constant and substantially equal to the distance between the upper end of the section —6— and diaphragms —11— so as to assure proper relation between the dia-

phragms and their corresponding tubes —8— when the section —6— is secured to the section —5—.

As previously stated practically all of the organ tones for any composition may be played within a range of five octaves either through the medium of an accompaniment manual, a solo manual and the pedals, or automatically through the medium of a perforated music sheet and certain devices controlled thereby for selectively energizing the stop magnets whereby any stop may be played as solo, accompaniment or pedal individually or the pedals or pedal stops may be played simultaneously with either the solo or accompaniment stops.

To this end, certain devices for selectively energizing the stop magnets —16— may be incorporated in the organ case, said parts consisting, in this instance, of a contact box —18— upon which is mounted a plurality of parallel horizontal rows of U-shaped electric conductors —19— arranged in uniformly spaced relation vertically and the several rows insulated from each other by their supporting box, while those of each row, in this instance, sixty-one in number, are also arranged in uniformly spaced relation horizontally and insulated from each other by the same box and representing the sixty-one notes of the corresponding stop of a five octave organ, the conductors representing corresponding notes being preferably arranged in vertical columns one over the other.

These conductors —19— are preferably made of spring wire of uniform length and are secured near their closed ends to one of the upright walls of the box —18— so that their opposite arms may extend in parallelism some distance from said upright wall to permit them to move vertically into and out of contact with their respective stop bars as will be hereinafter more fully explained.

Stop bar action

Each conductor —19— is electrically connected by a separate wire —16'— to its corresponding magnet —16— and therefore, its opposite contact arms —19'— and —19''— are connected to the same magnet for use in connection with separate stop bars —20— and —20'— for playing the corresponding pipe either as "accompaniment" or "solo" as may be determined by the selective adjustment of one or the other of said bars.

The several conductors are preferably arranged in parallel diagonal planes relatively to vertical and horizontal planes to bring the two arms or contact bristles —19'— and —19''— of each conductor —19— in different vertical planes and also in different horizontal planes so that like bristles of each will be horizontally aligned for simultaneous contact with their corresponding stop bars, while like bristles of the several rows will be ver-

tically aligned for simultaneous contact with the adjacent portions of all of the stop bars when the bristles are operated by their respective "stickers" —21— and —21'— presently described.

The stop bars —20— and —20'— are preferably made of wood or other insulating material and are slidable endwise on the box —18— directly over the free ends of their respective horizontal rows of contact bristles —19— and —19''— and may therefore, be respectively designated as "accompaniment" stop selecting and "solo" stop selecting bars.

Each of the bars —20— and —20'— is provided with a plurality of metal contact members —23— spaced longitudinally to correspond to the horizontal spacing of the contact bristles of its cooperative row but are electrically connected to each other and to the corresponding magnets —16—, leaving intervening insulated portions normally overlying adjacent contact bristles when the bars are adjusted to their inactive positions.

The stop bars —20— and —20'— of each set are operated by separate pneumatics —22— and —22'— which in turn are controlled by separate electro-magnets —24— and —24'—, one for each stop bar, said magnets being mounted upon one or more wind chests —25— having a vacuum chamber —V— and separate valve chambers —25'—, one for each of the magnets —24— and —24'—.

Each valve chamber —25'— has a pair of opposed ports —26— and —26'— leading respectively to the atmosphere and to the adjacent vacuum chamber —V— and controlled by an armature valve —27— which normally closes the port —26'— but is adapted to be operated by the energizing of its corresponding magnet —24— or —24'— to open the port —26'— and to close the adjacent atmosphere port —26—.

The pneumatics —22— and —22'— are connected by separate tubes —22''— to their respective valve chambers —25'— and are therefore normally open to the atmosphere through their normally open atmosphere ports —26— and thereby inflated or distended.

Energizing of any one of the magnets —24— or —24'—, will cause the adjacent valve —27— to close its atmosphere port —26— and to open its port —26'— for connecting said pneumatic with the vacuum chamber —V— and deflating the same to operate the corresponding stop bar and to register its contact members —23— with the contact bristles of the adjacent horizontal row ready for playing the notes of the selected stop or stops for the "accompaniment" or "solo" manuals.

As previously explained, the contact bristles —19'— and —19''— are arranged in separate vertical rows and those of each ver-

tical row are connected to a separate "sticker" —21— or —21'— for simultaneous operation into and out of contact with the corresponding "stop" bars —20— and —20'— for selectively controlling the "accompaniment" and "solo" playing.

These stickers are connected to and are actuated by separate pneumatics —28— and —28'— which in turn are selectively operated and controlled by separate electro-magnets —30— and —30'—, one for each pneumatic, said magnets being mounted upon one or more wind chests —29— having a vacuum chamber —V— and a plurality of valve chambers —31— and —31'—, one for each magnet, connected by separate tubes —32— and —32'— to their respective pneumatics —28— and —28'—, Figure 2.

Each valve chamber —31— and —31'— is provided with opposed ports —33— and —33'— and an armature valve —34— controlling the ports of each set, the ports —33— being normally open to the atmosphere to inflate their respective pneumatics —28— and —28'— while the ports —33'— connect their respective valve chambers to the adjacent vacuum chamber —V—.

The armature valves —34— normally close their respective ports —33'— thus permitting atmospheric air to enter and inflate the corresponding pneumatics —28— and —28'— but are adapted to be operated by their respective magnets —30— and —30'— to close their atmosphere ports —33— and to open their companion ports —33'— to connect their respective pneumatics with the vacuum chamber —V— and thereby to operate said pneumatics for the purpose previously explained.

In addition to the means for selectively operating and controlling the manual "accompaniments" and "solos" as previously described, suitable means is provided for selectively operating and controlling the thirty lower notes of the organ range or "pedal" action independently of or simultaneously with either the manual "accompaniment" or manual "solo" parts, and to this end is provided a supplemental contact box —18'— carrying any suitable number of horizontal rows of contact bristles —19'—, "stop bars" —20'—, and "stickers" —21'— similar to the like parts previously described except that they are single instead of double.

Pedal solo selector

That is, each conductor consists of a single spring wire contact bristle —19'— instead of the U-shaped conductors —19— previously described and each horizontal row may have thirty contact bristles, one for each of the thirty lower notes of the organ range of eight octaves to be used for pedal solo playing or in conjunction with either the

manual "accompaniment" or manual "solo" parts, those of the several rows representing like notes being arranged in vertical alinement and operatively connected to their respective stickers —21'— in a manner similar to those previously described.

Associated with the several horizontal rows of contact bristles —19'— of the pedal action is a corresponding number of "stop" bars —20'—, each having a number of contact members —23—, one for each contact bristle of the cooperative row, the contact members of each bar being electrically connected to each other and to a source of electric energy as —B'— while the contact bristles —19'— are separately connected to their respective pipe-controlling magnets —16— for controlling the pedal pipes in a manner similar to that previously described, for the "accompaniment" and "solo" playing.

The "stickers" —21'— are operatively connected to and actuated by separate pneumatics —28'— which, in turn, are controlled by separate electro-magnets —30'—, said magnets being mounted upon a supplemental wind chest —29'— containing a vacuum chamber —V—, and a plurality of valve members —31'—, Fig. 3, each connected by a tube —32'— to its corresponding pneumatic —28'— and provided with opposed ports —33— and —33'— and an armature valve —34— similar to the like parts of the manual "solo" selectors previously described.

It is now evident that by moving any one of these bars —20— or —20'— to one position for registering its contacts —23— with the adjacent contact bristles —19'— or —19'— of the corresponding conductors —19— and then moving any one or more of those bristles into contact with the registering contact member or members —23— will close the circuit through and thereby energize the corresponding magnet or magnets —16— to sound the corresponding pipe or pipes —A'— of that particular stop.

For example, any contact bar —20— and cooperative row of contact arms —19'— of the corresponding conductor —19— may be used to play the pipes of the corresponding stop as an "accompaniment", or any contact bar —20'— and its adjacent arms —19'— of the same conductor —19— may be used to play the pipes of the same stop as a "solo", while any contact bar —20— and corresponding row of bristles —19'— of the contact box —18'— may be used for playing the pedal pipes alone or in conjunction with the manual "accompaniment" or "solo."

Console parts

The essential parts of the console are shown more or less diagrammatically and comprise an accompaniment manual —C'— and a solo manual —D'—, Figure 2, each having a series of, in this instance, sixty-one keys covering

70

100

105

110

115

120

125

130

a range of five octaves, and a corresponding number of stop-controlling tablets —E'—, Figure 4, all of which parts are adapted to be operated for manual organ playing if desired, the stop tablets —E'— being preferably arranged along the manual key-board.

The console also comprises a tracker bar —F'—, Figures 1, 2, 3 and 4, and a perforated music sheet —G'—, Figure 5, which is adapted to be moved across the tracker bar by any suitable mechanism, not necessary to herein illustrate or describe, for registering its perforations with the various ducts of the tracker bar and thereby controlling the operation of various devices in the console for selectively operating the various organ parts previously explained.

The tracker bar —F'— as shown, is provided with a single row of ducts, sixty-one of which are designated as "notes", twenty as "solo divisions and stops", ten as "pedal solo divisions", one each for "pedal cancel", "stop cancel", "solo cancel" and "solo to stop switch" as indicated in Figure 5 upon the music sheet —G'— which may be provided with a corresponding number of rows of perforations similarly grouped and the several groups designated by corresponding titles, it being understood that for brevity and clarity, the music sheet shown includes only a limited number of rows of perforations in the "notes" group, the "solo division and stop" group and the "pedal solo division" group.

The several "note" ducts of the tracker bar —F'— are connected by separate tubes —35— to separate passages —35'— in a vent chest —36—, and the passages —35'— are connected by separate tubes —36'— to separate pneumatics —37— which are preferably assembled in groups of three in each group within the vacuum chambers —V— of a plurality of, in this instance, twenty solo selector blocks —38—, one for each group.

Each of the pneumatics —37— is adapted to operate and control a pair of normally open electric switches —39— and —39'— which are connected in circuit with their respective magnets —30— and —30'— for controlling the operation of the corresponding pneumatics —28 and —28'—, Figure 2.

Within each block —38— is also mounted an additional pneumatic —37'— and a double switch having two terminals —40— and —40'— and a movable contact member —40''— normally in contact with the terminal —40— and adapted to be operated by the pneumatic —37'— to break said contact and to contact with the terminal —40'— for controlling the energizing of the switches —39— and —39'— of the corresponding group.

For this purpose the movable members of the switches —39— and —39'— of each group are electrically connected by wires —41— and —41'— to the terminals —40— and —40'— respectively of the correspond-

ing block —29— while the fixed terminals of the switches —39— and —39'— of each group are connected by wires —42— and —42'— to their respective magnets —30— and —30'—, Figure 2.

It therefore follows that if any one or more of the "accompaniment" stop bars —20— are adjusted to register their contacts —23— with the cooperative rows of bristles —19'—, and any one or more of the "note" perforations of the music is registered with its corresponding ducts —35— in the tracker bar, atmospheric air will be admitted to the corresponding pneumatics —37— for closing both of the switches —39— and —39'— and thereby energizing the cooperative magnets —30— and their pneumatics —28— for lifting their respective bristles —19'— into contact with the registering bar-contacts —23— which, in turn, closes the circuits through the corresponding magnets —16— and causes the sounding of their respective pipes —A'—.

Or, the same result may be produced manually by the operation of the keys of the manual —C'— through the medium of electric switches —c'— and wires —c'— leading therefrom to the corresponding magnets —30—, Figure 2, in which the electric switches are separately operable by their respective keys but in either case any note or combination of notes throughout the entire range of the key-board may be played on any accompaniment stop within its range.

During this "accompaniment" playing the pneumatics —37'— and their respective switches —40'— may remain in their normal positions but, as previously stated, each pneumatic —37'— controls its corresponding group of primary pneumatics —37— and their respective pairs of switches —39— and —39'— and determines the number of (in this instance twenty) divisions or groups into which the sixty-one "note" ducts and note perforations of the tracker bar and music sheet, respectively, are divided.

These divisions and also the ducts and perforations of each division are arranged in sequence from left to right corresponding to the ascending gradations of the chromatic scale such as (C, C#, D), (D#, E, F,) (F#, G, G#) and so on through the several octaves and it therefore follows that the notes of any one or more divisions of any one or more "stops" may be played as "solo" with any one or more different divisions of the same "stop" or a different "stop" as "accompaniment" by adjusting the corresponding stop bars to their playing positions and operating the desired primary pneumatics —37—.

The music sheet —G'— as illustrated shows only six of the twenty groups of rows of "note" perforations designated as "Div. 1", "Div. 2", "Div. 3" and so on, and at the

right hand of the "note" perforations are a corresponding number of the twenty rows of "solo division and stop" perforations numbered 1, 2, 3 and so on to correspond with the number of groups, while the tracker bar is 5 provided with similarly designated ducts —43— with which the corresponding perforations are adapted to register.

These twenty tracker ducts —43— are connected to a corresponding number of separate channels —43'— in a pneumatic switch box —44—, each channel having a series of, in this instance three, pneumatic valves —45—, —45'— and —45''— controlling a corresponding number of air tubes or conduits —46—, —46'—, and —46''— which, in turn, are respectively connected to separate valve chests —47—, —47'— and —47''—.

The pneumatics —45—, —45'— and —45''— of the several channels —43'— are arranged in horizontal rows and those of the several rows are connected by separate ports —48—, —48'— and —48''— to adjacent air chambers —49—, —49'— and —49''—, one 25 for each row, each channel being provided with a restricted vent —44'—.

The pneumatics —45— serve to open and close their respective tubes —46— and are all controlled from a single valve chest —50— having separate valve chambers —51— and —51'—, a vacuum chamber —V—, an air chamber —52— and a primary pneumatic —52'—, the valve chamber —51— being connected by a tube —50'— to the air chamber —49—, Figures 2 and 4, and provided with opposed ports leading respectively to the vacuum chamber —V— and to the air chamber —52—.

These ports are controlled by a valve 40 —53— which normally closes the atmosphere port and opens the vacuum port for normally deflating the pneumatics —45— and thereby opening the tubes —46— of that row.

The valve chamber —51'— is connected by 45 a passage —54— and a restricted passage —54'— to the pneumatic —52'— and to the vacuum chamber —V— respectively and is also connected by separate tubes —55— and —55'— to similar but separate valve chests —56— and —56'— which, in turn, are connected by tubes —57— and —57'— to the air chambers —49'— and —49''— for a purpose presently described, the air tubes —55— and —55'— being controlled by separate poppet 55 valves —58— and —58'— in the chamber —51'—.

The valve chest —47—, Figure 2, is provided with a plurality of, in this instance, twenty vacuum chambers —V—, an air chamber —59—, common to all of the vacuum chambers, valve chambers —59'— connecting the corresponding chambers —V— and —59—, and primary pneumatic chambers —60— which are connected by separate bypasses —60'— to their respective valve chambers

—59'— and are provided with separate ports —61—, each connected to its corresponding tube —46— and controlled by a poppet valve —61'—.

The valve chambers —59'— are provided with double valves —62— each controlling 70 communication between its chambers —V— and —59— and also between said chambers and the adjacent by-pass —60'— while each by-pass is connected by a tube —62'— to its corresponding "solo" controlling pneumatic 75 —37'—, Figure 2.

Associated with the "solo division" valve chest —47— is a "solo cancel" valve chest —63— having a vacuum chamber —V—, a primary pneumatic —63'— and a valve chamber —64— provided with opposed ports —64'— and —64''— leading respectively to the vacuum chamber —V— and to the atmosphere and controlled by a double valve —65—, Figure 2.

The valve chamber —64— is connected by a tube —65'— to the air chamber —59— which is common to all of the valves —62— and is normally open to the atmosphere through the port —64''— while the pneumatic —63'— is connected by a tube —66— to the "solo cancel" tracker duct to be controlled by a perforation in the "solo cancel" row of the music sheet.

Now, if any one or more of the "solo" stop bars —20— are adjusted to register their contacts —23— with the bristles —19''— of the corresponding row, the registration of a perforation in any one or more of the twenty "solo division and stop" rows of the music sheet (Fig. 5) with the corresponding duct —43— Figure 2, will allow atmospheric air to enter its tube —46—, open the valve —61'— and inflate the pneumatic —60— for operating the adjacent valve —62— to close its vacuum port and open its atmosphere port.

This allows the atmospheric air to enter the by-pass —60'— and pneumatic —60— for closing the valve —61— and thereby allows the atmospheric air to pass through the tube —62'— for inflating the "solo" controlling pneumatic —37'—, which causes the switch member —40''— to break contact with the terminal —40— and to make contact with the terminal —40'— so that the registration of any "note" perforation with its corresponding tracker duct in the selected "solo division" or group will cause the operation of the corresponding pneumatic —37— to close the switch —39— and —39'— and thereby, through the closed contacts —40'— and —40''—, energize the corresponding "solo" magnet —30'— for effecting the operation of its selected set of bristles —19''— and consequent sounding of the corresponding pipe —A'— as previously explained without in any way interfering with the free operation of any of the other 130

divisions or groups for "accompaniment" playing.

Or, the magnets —30— may be energized to produce the same tonal effects by the manual operation of the keys of the "solo" manual —D— through the medium of electric switches —d'— one for each solo key, and wires —d''— and —42'— leading to said magnets —30'—.

- 10 Any previously selected and operated "solo" controlling pneumatic and effects produced thereby may be automatically canceled by the registration of a perforation in the "solo cancel" line of the music sheet with its corresponding tracker duct —66—, Figure 2, whereby the valve —65— will be operated by the inflation of the pneumatic —63'— to close its adjacent atmosphere port and connect its vacuum chamber —V— with the then open corresponding by-pass —60'— for deflating the pneumatics —60— and —37'— connected thereto and allowing the contact member —40'— to return into contact with the terminal —40—.

25 *Pedal control*

It will be seen from the foregoing description that the twenty "divisions" or groups of three each of the note perforations and their tracker ducts, Figure 2, may comprehend the entire compass of a five octave or sixty-one note organ and may be used for selectively playing the "accompaniment" or "solo" stops throughout the range of both 30 the "accompaniment" and "solo" manuals but in as much as the lower thirty notes are also to be operated by the "pedal" action, they may be divided into ten groups or "pedal solo" divisions of three in each group 35 by devices similar to those previously described except that the "accompaniment" switches —39— contact terminal —40—, and also the "accompaniment" bars —20— and their respective rows of bristles —19'— are 40 omitted and the single "solo" parts used as in Figure 3.

That is, each air chamber —35'— of the vent chest —36— within the pedal range is connected by a separate tube —36''— to a 45 corresponding number of primary pneumatics —37''— which, in turn are arranged in groups of three in each group, within separate (in this instance ten) switch blocks —38'—, one for each group, each block also containing an additional pneumatic —37''— one for each group.

Each pneumatic —37''— controls a normally open electric switch —39'— while the pneumatic —37''— of each group controls a 50 normally open electric switch —40'''— and the three switches —39''— of each group are connected in multiple with the corresponding switch —40'''— so that if any one of the switches —40'''— is closed by the inflation of its corresponding pneumatic

—37''— it will place all of the movable switch members of that group in electrical connection therewith.

Now, if any note perforation of that group is registered with its corresponding tracker duct it will cause the operation of the selected pneumatic —37''— and its switch —39''— for energizing the corresponding magnet —30'— and playing the selected note of any particular stop which may be selected.

Otherwise, the parts for selectively operating, locking and canceling the pedal solo controlling pneumatics —37''— and —37'''— are similar to the parts for operating, locking and canceling the pneumatics —37— and —37'— previously explained and aside from the differences noted, the same reference characters are applied to corresponding parts.

20 *Stop bar action*

As previously stated, the pneumatic switch box —44— is provided with thirty channels —43'— leading to their respective tracker ducts —43—, and controlled by thirty rows of perforations in the music sheet, twenty for the "solo division and stop" selection and ten for the "pedal solo division" and stop selection as shown in Figure 5, and that each channel is connected by three tubes —46—, —46'— and —46''— to the lock valve chambers of the "lock valve chests" —47—, —47'— and —47''— all having similar parts designated by like reference characters while the three rows of air chambers —49—, —49'— and —49''— are connected by tubes —50'—, —50''—, —57— and —57'— to their respective valve chests —50—, —56— and —56'—.

The valve chests —56— and —56'— are similar and are used to selectively control the operation of the pneumatics —45'— and —45''— of their respective rows, and thereby to selectively control the operation of the movable parts of the "stop lock valve chests" —47— and —47''— corresponding to said pneumatics.

For this purpose, each valve chest —56— and —56'— is provided with a valve chamber —67— connected by opposite ports to a vacuum chamber —V— and to the atmosphere respectively by a double valve —67'— controlling both of said ports, and a pneumatic —67''— for operating the valve —67'—, the valve chambers —67— of the chest —56— and —56'— being respectively connected by the tubes —57— and —57'— to the air chambers —49— and —49''— for controlling the pneumatics —45'— and —45''— of the corresponding rows, each chest being also provided with an air chamber —68— having a vent —68'— leading to the vacuum chamber —V—, and an air passage —68''— leading to the pneumatic —67''—.

The tubes —55— and —55'— controlling the valves —58— and —58'—, previously de-

70

80

100

105

110

115

120

125

130

scribed, are connected to the air chambers —68— of the valve chests —56— and —56'— respectively, while the pneumatics —67''— of the same valve chests are respectively connected by separate ducts —69— and —69'— to the tracker bar —F'—, it being understood that one valve chest, as —56—, controls all of the pneumatics —45'— and that the other valve chest —56'— controls all of the pneumatics —45''—.

10 The "stop lock" valve chests —47— and —47''—, Figure 4, like the "pedal solo division" lock valve, Figure 3, are similar to "solo division" lock valve, Figure 2, previously described, and their various parts may therefore, be designated by the same reference characters.

15 The air chambers —59— of the valve chests —47— and —47''— are connected to separate valve cancel chests —63— which are similar to those previously described and have their various parts designated by the same reference characters with the single exception that the tubes —66'— leading to the tracker bar 20 are connected to each other and to the tracker duct corresponding to the row of perforations marked "Stop cancel" in the music sheet.

25 "A "stop contact" box —38"—, Figure 4, contains a vacuum chamber —V—, two sets 30 of electric switches —70— and —70'—, in this instance thirty in each set, and corresponding sets of the same number of primary pneumatics —71— and —71'—, each adapted to operate its individual switch.

35 The electric switches —70— and —70'— are connected in the circuits of their respective electro-magnets —24— and —24'— previously described, while the pneumatics —71— and —71'— are connected by separate 40 tubes —72— and —72'— to their respective by-passes —60'— of the valve chests —47— and —47''— thus completing the automatic stop control mechanism but if desired, the energizing of the same magnets for the same 45 purposes may be controlled at will by the operation of any one or more of the "stop" tablets —E'— and their respective electric switches —e'— which are connected in circuit with their respective magnets.

50 In Figure 7, which is a rear face view of the contact box for the bristle, portions of each of the five octaves of the bristles for the several stops are shown reading from left to right, as part 1, part 2, part 3, part 4 and part 55 5; part 1 being the treble end showing the bristles controlling the pipes —C— and —B—; part 2, the bristles for pipes —C— and —B— one octave lower; part 4, the bristles for the 12th or $2\frac{2}{3}'$ pitch pipes as 60 —G— and —F#—; and part 5, the bristles for the pipes —C— and —B—, four octaves lower.

65 The bristles —19— of each row cooperate with a corresponding number of pairs of stop rods —20— and —20'— one of each pair

being adjustable for accompaniment playing and the other for solo playing for the several stops or sets of pipes represented by the several rows of bristles as previously explained and these several rows may be designated respectively from top to bottom as —2' pitch, $2\frac{2}{3}'$ or 12th pitch, 4' pitch, 8' pitch and 16' pitch.

70 The bristles —19— representing like notes of the various horizontal rows representing the stops of different pitch, may be electrically connected in octaves or in any intermediate or mutation pitch by wires —80— only one of which is shown in Figure 7 as connecting the —C— bristles of the 16' stop, part 1, with the —C— bristles of the 8' stop, part 2, the —C— bristles of the 4' stop, part 3, the —G— bristles of the $2\frac{2}{3}'$ or 12th stop, part 4, and the —C— bristles of the 2' stop, part 5.

Operation

85

In this particular instrument provision is made for the operation of sixty stops involving the use of a corresponding number of stop bars, some for controlling the "accompaniment" and others for controlling the "solo" parts, the sounding of each pipe of each stop being selectively interchangeable from "accompaniment" to "solo" and vice versa by reason of the double contact bristles —19— and —19''— having single leads —16— to their respective pipe magnets —16—, Figure 2, as previously explained.

The operations of the "accompaniment" bars —20—, Figure 4, are separately controlled by the opening and closing of the corresponding tubes —46'— through the medium of their respective pneumatics —45—, while the operations of the "solo" bars —20'— are separately controlled by the opening and closing of the corresponding tubes —46''— through the medium of their respective pneumatics —45''—, Figure 4.

The selections of the "solo divisions" or groups of three notes each for any selected stop are controlled by the opening and closing of the corresponding tubes —46— through the medium of their respective pneumatics —45—, Figure 4 all of which are normally deflated by vacuum pressure from the valve chest —50— to open said tubes as previously explained.

Under these conditions any one or more of the sixty "stops" may be brought into action by the registration of one or more perforations in any one or more of the twenty rows in the right hand margin of the music sheet with one or the other of the tracker ducts —43— of the corresponding stop-selecting ducts —46'— or —46''— and at the same time any one or more of the manual solo divisions may be automatically selected and operated by the registration of any one or more perforations in any one or more of the same rows with the ducts —43— of the cor-

115

120

125

130

responding solo division-selecting ducts —46—.

For example, assuming that all of the "solo" and "accompaniment" stops are canceled to bring all of the automatic playing parts to their normal positions as in Figure 1 and that it is desired to automatically play an accompaniment part on any particular stop, then a perforation in the moving music sheet registering with the tracker duct —69—, Figure 4 will place all of the pneumatics —45'— of the chamber —49'— under vacuum pressure, thereby opening all of the corresponding tubes —46'—.

If, now, another perforation in the music sheet is brought into registration with the tracker duct —43— corresponding to the particular stop selected, the air pressure admitted to the adjacent tube —46'— will temporarily open its check valve —61'—, inflate the adjacent pneumatic —60— and lift the corresponding valve —62— to connect the atmosphere port —64'— of the cooperative valve chest —63— with the corresponding pneumatic —71— of the switch box —38'— through the connecting passages —60'— and —72—.

The check valve —61'— then closes by its own weight and air pressure, leaving the pneumatic —71— inflated to close its switch —70— which, in turn, closes the electric circuit through its electro-magnet —24— and thereby operates the adjacent valve —27— to place the corresponding pneumatic —22— in communication with the vacuum chamber for deflating the same and causing it to adjust its stop bar —20— to playing position, Figure 4.

Now, as the note perforations in the music sheet register with their respective tracker ducts —35—, Figure 2, air pressure through the tubes —35— and —36'— will inflate the corresponding pneumatics —37— to close their respective pairs of electric switches —39— and —39'— in the switch box —38—.

The switch members —40— and —40'— of each block —38— are connected in series with the switches —39— and —39'— respectively of the corresponding group while the switch member —40'— is normally in contact with the switch member —40— and out of contact with the switch member —40'— and therefore the closed switch —39'— controlling the adjacent "solo" group selecting pneumatics —37'— is "dead".

Under these conditions the closed switches —39— will close the circuits through the corresponding electromagnets —30— and operate their respective valves —34— thereby connecting their respective pneumatics —28— with the vacuum chamber —V— of the chest —29—, Figure 2 for operating said pneumatics and their respective stickers —21— and causing the corresponding bristles

—19'— to make electrical connection with their contact members —23— on the previously adjusted stop bar —20—.

This closing of the bristles —19'— against the contacts —23— closes the circuit through the corresponding electro-magnet —16— for operating the adjacent valve —15— and causing the speaking of the pipe —A'— of the selected stop as an "accompaniment" part of the musical selection, during which the "solo" parts are rendered inactive by reason of the open switch at —40'—.

In like manner, any number of stop bars —20— may be drawn individually or in combinations for playing the corresponding stop or stops as "accompaniment" as long as the solo selective pneumatics —37'— remain in their normal positions with their switch members —40'— in contact with the terminals —40—, it being understood that the switches —39— and —39'— are intermittently closed and opened by the presence or absence of note-perforations in the music sheet registering with their respective tracker ducts —35—.

If it is desired to switch from "accompaniment" to "solo" a perforation in the music sheet is caused to register with the tracker duct —69'— to admit air to the pneumatic —67'— of the chest —56— for operating the valves —67'— and —53— and thereby causing all of the pneumatics —45'— to open their respective tubes —46'— and at the same time causing all of the pneumatics —45— to close their tubes —46—.

Now, if a perforation in the music sheet is caused to register with any one of the ducts —43—, air will be admitted to the corresponding tube —46'—, opening the check valve —61'— and operating the pneumatic —60— and valve —62— to admit air from the chest —63— through the tube —72'— to the corresponding pneumatic —71'—, Figure 4.

The admission of air to the pneumatic —71'— will cause the closing of the switch —70'— thereby closing the circuit through the corresponding electro-magnet —24'— which, in turn, will operate the adjacent valve —27— and place its pneumatic —24'— in communication with the vacuum chamber —V— of the chest —29— resulting in the operation of the corresponding "solo" stop bar —20'— to its playing position.

The registration of the note perforations of the music sheet with their respective tracker ducts —35— will then cause the closing of the switches —39— and —39'—, as before, for energizing the electro-magnets —30'— and thereby causing the operation of their corresponding valves —34— and pneumatics —28'— which, in turn, will operate the sticker —21'— to engage the bristles —19''— with the contacts —23— of the

previously drawn stop bar —20'— and cause the speaking of the selected pipe for that particular stop for "solo" playing.

In like manner, all of the stop-bars —20'— 5 may be drawn individually or in different combinations for playing the individual "solo" notes of any selected group or combinations of groups.

In Figure 1, the five octaves of note ducts 10 —35— of the tracker bar are shown as connected to a corresponding number of ducts —35'— in the vent chest —36—, while the twenty tracker ducts —43— at the right hand end and the ten tracker ducts —43— at the 15 left hand of the tracker bar are connected to corresponding numbers of channels —43'— in the switch box —44—.

The five octaves of note ducts —35'— in 20 the vent chest —36— are arranged in groups of three in each group and those of each group are connected by tubes —36'— to an equal number of the pneumatics —37— in each of the twenty switch blocks —38— so that the twenty switch blocks contain altogether sixty-one of the pneumatics —37—, or 25 one for each note of a five octave organ.

Each block —38— also contains one of the pneumatics —37'— and these twenty pneumatics —37'— are connected by separate tubes —62'— to their respective by-passes —60'— of the valve chest —47— as previously described.

Each pneumatic —37— controls a pair of switches —39— and —39'— while each pneumatic —37'— controls all three pairs of switches —39— and —39'— of its corresponding group for selectively soloizing the notes of any selected group throughout the five octaves.

40 The valve chest —47— which is connected to the solo selecting pneumatics —37'— is also connected by twenty of the tubes —46— to the corresponding twenty channels —43'— of the switch board —44— for controlling 45 the passage of air from their respective tracker ducts —43— to said valve chest —47—.

The thirty lower notes or pedal ducts —35'— of the vent chest —36— are connected 50 by tubes —36'— to a corresponding number of pneumatics —37'— which are arranged in groups of three in each group in a manner similar to the grouping of the pneumatics —37—, previously described, those of each 55 group being contained in separate switch blocks —38— (ten in number) together with a single pneumatic —37'''—, one for each group, Figure 3.

These ten pneumatics —37'''— are connected 60 by a corresponding number of tubes —62'— to a second valve chest —47— which in turn, is connected by tubes —46— to their respective channels —43'— in the switch box 65 so that air admitted to any one of the corresponding tracker ducts —43— will cause

the operation of its pneumatic —37'''— to close the adjacent switch —40'''— ready for pedal-solo-playing of the notes of that group.

The three electric switches —39'— of each group are electrically connected to the single switch —40'''— of the same switch block —38'— and therefore, if any one of the switches —40'''— is closed in the manner described, the closing of any one of the three switches —39'— of that group by air admitted to its pneumatic —37'''— through the corresponding tracker duct —35— will energize its magnet —30'—, Figure 3, and thereby cause the selected pedal-bristles —19'— to contact with the members —23— of the previously drawn stop-bar —20'— and consequent speaking of the selected pipe of that particular stop as previously explained.

In like manner any one or more groups of 70 pedal notes may be soloized while any of the "accompaniment" or "solo" stops are drawn, 75 it being understood that the simultaneous playing of "pedal solo" and accompaniment or "solo" notes in the same group is seldom if ever required and therefore, the note perforations are arranged to avoid those conditions.

Any one or all "stops" selected for playing 80 may be cancelled at once and at any time during the playing operation by providing the 85 music sheet with the necessary perforations to register with its tracker duct —63'— at the proper time and thereby to cause the operation of the pneumatics —63'— and valves —65—, Figure 4, for connecting the chambers —59— and —60— with the vacuum chambers —V— of the chests —63—, thus 90 equalizing the air pressure in said chambers and also in the corresponding pneumatic —71— and allowing the switch —70— to 95 open.

In a similar manner the parts for selecting the "solo divisions" and "pedal-solos" may be 100 canceled by providing the music sheet with 105 perforations to register with the tracker ducts —66—, Figure 2 or —66—, Figure 3 for causing the switch members —40'— and —40'''— to their normal positions.

The valve chests —63— for canceling the "accompaniment" stops and "solo" stops are 110 shown at the right hand of Figure 1, while the similar chests —63— for canceling the "solo divisions" and pedal "solos" are shown 115 at the left hand of the same figure.

In Figure 5 is shown a fragmentary portion 120 of a music sheet —G'— having eighteen of the sixty-one lines of note perforations divided into groups of three lines each and the several groups numbered in sequence from 125 left to right, the right hand margin of the sheet being provided with six of the twenty lines of "solo division" and "stop" perforations similarly numbered to represent the several groups of note perforations.

The left hand margin of the sheet is pro- 130

vided with four of the ten lines of "pedal solo division" perforations numbered in sequence from left to right and just at the left hand of the four more or less lines of perforations for the "pedal cancel," "stop cancel", "solo cancel" and "solo to stop switch".

The note perforations which are represented as clear represent "accompaniment" parts; those with hyphen inserts (-) "solo" parts; those with small circles (○) "pedal" parts and those with small circles and hyphens (⊖) "solo" and "pedal" parts played together.

These several lines of perforations as illustrated are arranged to show some of the many combinations which may be used in playing musical compositions.

For example, at the beginning of the selection, in cross line —A—, are the "cancel" perforations for canceling the "pedal," "stop" and "solo" actions respectively, followed by another cross line —B— of perforations in the "solo to stop switch" line, and in lines 1, 3 and 4 of the solo adapted to register respectively with the tracker duct —69'—, Figure 4, and with the three corresponding tracker ducts —43— for setting the pedal stop, the solo stop and the accompaniment stop to their playing positions and also for selectively soloizing the notes in "Div. 1."

A note perforation (a) beginning in cross line —C— of "Div. 1" line is selected to be played as pedal solo by a short perforation at the intersection of the same cross line with the corresponding pedal division line, but is canceled by the perforation in cross line —E— in the "pedal cancel" line.

Beginning at the cross line —D— are "accompaniment" note perforations and a note perforation in "Div. 4" line soloized by a perforation in the corresponding "solo division" line 4, other notes in "Div. 4" and in "Div. 5" being soloized by the perforations in line 4, cross line —D— and another perforation in cross line —F—, "Div. 5".

At cross line —G— and pedal division line 1 is a pedal solo selecting perforation for soloizing the perforation as —f— in Div. 1, but is canceled by a pedal cancel perforation in cross line —J— so that the remaining portion of the perforation —F— will be played as accompaniment.

In cross line —H— and "solo cancel" line is a perforation for canceling the previously soloized notes, and at the same cross line and cross line H—H, in solo division line —6— is a relatively longer perforation for soloizing the notes in Div. 6.

In solo division lines 3, 4 and 5 at cross lines —I—, —K— and —L— are other perforations for soloizing the notes in the corresponding Div. 3, Div. 4, and Div. 5, the first part of one of the notes, as —j—, in Div. 3, cross line —M— being played as solo and then canceled at M so that the middle portion of the same note is played as accom-

paniment, while the last part is again soloized by the perforation at cross line N—N and division selecting line 3.

Other solo selecting perforations are provided at —N— line 2 and —O— line 1, for soloizing the notes in the corresponding "Div. 2" and "Div. 1" but are canceled and "Div. 1" soloized at (O—O) by reason of the longer perforation —r— thereby causing part of perforation —m— to be played as "solo" and the remaining part as "accompaniment".

At —P— the stops previously drawn stops are canceled by perforation —q— except that #1 and #4 are held over and two new stops #5 on the right hand and #3 on the left hand divisions are drawn and at —Q— note (y) is selected to play pedal solo and manual but is canceled at (R) leaving the central portion of note (y) to be played as "accompaniment" while at (S) the same note is again soloized without the pedal and is canceled at (T).

An accompaniment (2) begins at (T) but at (U) all stops and solos are canceled and another perforation (Z—Z) begins in the pedal cancel line for operating the roll to rewind the music sheet thus completing the playing and rewinding operations.

I claim:

1. In a player action for pipe organs, a wind-chest having separate air chambers one above the other, the upper chamber containing air under playing pressure and having its top wall provided with a vertical port for directing air to a sound producing pipe, the lower chamber containing air under pressure greater than that in the upper chamber, a pneumatic supported within the upper chamber and cooperating with the lower end of said port for controlling the passage of air from the upper chamber to the pipe and normally communicating with the lower chamber to close the port, and means forming a part of the player action for closing said communication and venting the pneumatic to open the port.

2. In a player action for pipe organs, a pipe chest comprising a pipe supporting section having relatively upright tubular ports for the pipes and a diaphragm supporting section having its diaphragms in direct coaction with and controlling the ports, said diaphragm supporting section being removable by downward displacement to withdraw the diaphragms from their respective ports without disturbing the pipe supporting section and pipes thereon.

3. In a player action for pipe organs, a pipe chest comprising a pipe supporting section having pipe ports in its top wall, a diaphragm supporting section removably secured to the underside of the pipe supporting section and forming therewith a pipe pressure air chamber, the diaphragm sup-

- porting section being provided with a higher-than-pipe-pressure-air-chamber, diaphragm pneumatics mounted on the diaphragm supporting section in direct cooperation with the lower ends of the ports for controlling the passage of air from the pipe pressure chamber to their respective pipes and normally in communication with the high pressure air chamber through means carried by the diaphragm supporting section for closing the diaphragms against their respective ports, and means carried by the diaphragm supporting section for closing said communication and simultaneously venting the diaphragm pneumatics.
4. In a player action for pipe organs, a pipe chest comprising a pipe supporting section having a relatively fixed tubular port, a diaphragm controlling said port, a diaphragm supporting section removably secured to the lower end of the pipe supporting section and forming therewith a "pipe-pressure-chamber," said diaphragm supporting section being provided with a "higher-than-pipe pressure" air-chamber normally communicating thru a passage with the diaphragm for closing the same against its port, and means on the diaphragm supporting section for cutting off communication between the high-pressure-chamber and said passage and connecting the passage with the atmosphere to permit the opening of the diaphragm by the air in the pipe pressure chamber.
5. In a player action for pipe organs, a sound-producing pipe, and web-controlled means for selectively sounding said pipe as "solo" or "accompaniment."
6. In a player action for pipe organs, a set of pipes constituting a "stop," and web-controlled means for selectively sounding any one of the pipes as "solo" or "accompaniment."
7. In a player action for pipe organ, a set of pipes constituting a "stop," and web-controlled means for selectively sounding any one of the pipes as "accompaniment" and other as "solo" at the same time.
8. In a player action for pipe organs, a sound-producing pipe, a "solo" selecting couple, an "accompaniment" selecting couple, means common to both of said couples and operable by either couple for sounding the pipe, and web-controlled means for selectively rendering either couple active.
9. In a player action for pipe organs, a set of pipes constituting a "stop," the pipes of said stop being arranged in groups, means for "drawing" the stop, and web-controlled means for selectively sounding the pipes of any group independently of the other groups.
10. In a player action for pipe organ, a sound-producing pipe and means for sounding the same including an "accompaniment" controlling couple, a "solo" controlling couple, web-controlled means for operating

both couples simultaneously, and web-controlled means for rendering either couple active and the other couple inactive at the same time.

11. In a player action for pipe organs, a group of sound-producing pipes, means for sounding said pipes including a plurality of "accompaniment" controlling couples, one for each pipe, a plurality of "solo" controlling couples, one for each "accompaniment" couple, web-controlled means for selectively operating the couples of each pair, and web-controlled means for rendering all of the couples for either part active and those of the other part inactive.

12. In a pipe organ having a plurality of "stops," web-controlled means for selectively "drawing" the stops, means for selectively sounding the pipes of the "drawn" stops, and web-controlled means for coupling the pipes of each octave of each stop to the pipes of the next octave of another stop.

13. In a player action for pipe organs, web-controlled means including an electro-magnet for controlling the speaking of a pipe, separate electric contacts in the magnet circuit and representing different stops, and web-controlled means for electrically connecting and disconnecting said magnet with either of said contacts.

14. In a player action for pipe organs having separate electro-magnets for controlling the speaking of individual pipes, each magnet circuit including therein a single conductor having a plurality of branches representing different stops, and web-controlled means for closing said circuit thru any of said branches.

15. In a pipe organ having separate electro-magnets for controlling the speaking of individual pipes, each magnet circuit including therein a single conductor having a plurality of branches representing different stops, and web-controlled means for closing said circuit thru all of the branches simultaneously.

16. In a player action for pipe organs, separate electro-magnets, each controlling an individual pipe, each magnet circuit including therein a single conductor having a plurality of branches, each branch representing a different stop, stop bars representing different stops and each provided with a contact member in the magnet circuit, each stop bar being adjustable to move its contact into and out of registration with its corresponding branch, separate devices for operating said branches into and out of engagement with the registering contacts of their respective stop bars and web-controlled means for operating said devices.

17. In a pipe organ having separate electro-magnets, each controlling an individual pipe, each magnet circuit including therein a single conductor having a plurality of branches, each branch representing a different stop, a corre-

sponding number of stop bars having contacts in said circuit and each bar adjustable separately to move its contact into and out of registration with its corresponding branch, means for selectively operating said branches to engage their respective bars and corresponding contacts when registered therewith, and web-controlled means for selectively shifting said bars to switch from one stop to another.

18. In a player action for pipe organs, a pipe, an electro-magnet controlling the sounding of the pipe and including in its circuit separate sets of cooperative contacts representing different stops separate pneumatics for closing the contacts, and means for separately energizing the pneumatics.

19. In a player action for pipe organs, a pipe, an electro-magnet controlling the sounding of the pipe and including in its circuit separate sets of cooperative contacts representing different stops, additional electro-magnets, one for each set of contacts means for selectively energizing the additional magnets, and separate devices actuated by the energizing of the additional magnets for closing their respective sets of contacts.

20. In a player action for pipe organs, a pipe, an electro-magnet controlling the sounding of the pipe and including in its circuit separate sets of cooperative contacts representing different stops, means for shifting one of the contacts of each set into and out of registration with its companion contact, and means for closing registering contacts of each set separately.

21. In a player action for pipe organs, a pipe, an electro-magnet controlling the sounding of the pipe and including in its circuit separate sets of cooperative contacts representing different stops, means for shifting one of the contacts of each set into and out of registration with its companion contact, separate pneumatics for closing the contacts, and means for selectively energizing said pneumatics.

22. In a player action for pipe organs, a pipe, an electro-magnet controlling the sounding of the pipe and including in its circuit separate sets of cooperative contacts representing different stops, additional electro-magnets, one for each set of contacts, web-controlled means for selectively energizing the additional magnets, and separate devices actuated by the energizing of the additional magnets for selectively closing their respective contacts.

23. In a player action for pipe organs, a pipe, a plurality of electric switches representing different stops, and a double switch common to all of the first named switches, web-controlled means for selectively connecting each contact of the double switch with the one of the first named switches and for automatically holding it in its adjusted position,

web-controlled means for closing the first-named switches, and means controlled by the closing of said switches for selectively sounding the pipe.

24. In a player action for pipe organs, a pipe, a plurality of electric switches representing different stops, and a double switch common to all of the first named switches, web-controlled means for selectively connecting each contact of the double switch with the one of the first named switches and for automatically holding it in its adjusted position, web-controlled means for closing the first-named switches, means controlled by the closing of said switches for selectively sounding the pipe, and web-controlled means for canceling the second-named web-controlled means.

25. A solo division and stop selection for pipe organs comprising a plurality of translating devices, and a web-controlled air duct controlling said devices.

26. A solo division and stop selection for pipe organs comprising a plurality of translating devices, a web-controlled air duct controlling said devices, and web-controlled means for canceling one of said devices.

27. A solo division and stop selection for pipe organs comprising a plurality of translating devices, a web-controlled air duct controlling said devices, and web-controlled means for switching the air from one to another of said devices.

28. In a player action for pipe organs, a group of ducts, and means for selectively playing different stops from said group.

29. In a player action for pipe organs, a note duct, and web-controlled means cooperating with said duct for selectively playing different stops.

30. In a player action for pipe organs, means for selectively playing different stops including separate electric switches, each representing a different stop, web-controlled means for simultaneously closing both of the switches, a double switch normally closing the circuit through one of the switches and breaking the circuit through the other switch, and web-controlled means for operating the double switch to break the normally closed circuit and to close the other circuit.

31. In a player action for pipe organs, a group of devices, each representing a different note and each operable to effect the playing of a stop, web-controlled means for effecting the operation of said devices individually, and web-controlled means for causing the devices of said group to effect the playing of a different stop.

32. In a player action for pipe organs, a plurality of groups of devices, each device representing a different note and each operable to effect the playing of a stop, additional devices one for each group and each operable in conjunction with the devices of its group

for effecting the operation of a different stop without interfering with the devices of the other groups, web-controlled means for effecting the operation of the first-named devices of each group and additional web-controlled means for effecting the operation of the second-named devices.

33. In a web-controlled player action for pipe organs, a note sheet having a group of note-controlling elements representing all of the notes to be played, and means for causing certain of said elements to effect the playing of one of the organs and other elements to effect the playing of a different organ.

34. In a record-controlled player action for pipe organs, a music sheet in which all of the notes to be played on all of the different registers, as Great, Swell, Pedal, Choir, etc., are arranged in one common group of perforations, means controlled by said perforations for selectively sounding the pipes, said music sheet having additional perforations and means controlled by the additional perforations for selectively switching from one register to another while any of the first-named perforations and any part of the length thereof remains in active position.

35. In a record-controlled player action for pipe organs characterized by the use of a music sheet having note perforations and additional short perforations, means controlled by the additional perforations for selecting the notes to be played on different registers, said music sheet having a cancel perforation and devices whereby the short perforations will remain effective until canceled, and means controlled by a single cancel perforation whereby the ducts of the selected perforations may in the meantime be used for other purposes (as drawing stops) without interfering with their solo selecting control.

36. In a record-controlled player action for pipe organs, means for controlling the speaking of the pipes of different pitch including a plurality of rows of electric conductors, one row for each pitch and those of each row arranged in octaves, one of the bristles of one row being electrically connected to other bristles of different rows for playing in different pitches.

37. In a record-controlled organ player, two or more sets of tone emitting elements, some of the sets being suitable for playing accompaniment notes, other sets for playing solo notes, a tracker bar, a music sheet and mechanism controlled thereby and arranged to normally play accompaniment parts only, and means controlled by the music sheet whereby any note or notes or any parts thereof may be played as solo notes on a different or the same set of tone-emitting elements.

38. In a record-controlled organ player having two or more registers of pipes, a tracker bar, a music sheet having perfora-

tions for all the notes to be played arranged in one group and normally controlling one or more registers, and additional perforations controlling mechanism whereby any note or notes or any parts thereof may be switched to play on a different register or registers.

39. In a record-controlled organ player, the combination with an organ adapted to be played in different registers, as Great, Swell, Pedal, Higher, Echo, etc., of a player mechanism and a controlling music sheet therefor, the music having perforations for normally playing one register only, and mechanism including a plurality of additional perforations for switching parts of the mechanism to cause the playing of all or parts of certain notes on a different register.

40. In a record-controlled organ player, the combination with an organ having instrumentalities for sounding both accompaniment and solo notes, of a player mechanism and controlling music sheet therefor, said music sheet having perforations normally playing the accompaniment notes only, and a plurality of additional perforations controlling the playing of solo notes from any or all of said accompaniment perforations.

41. In a record-controlled organ player having pipes or other sound-producing elements adapted to be played as accompaniment, solo or pedal, a player mechanism and controlling music sheet therefor, said player mechanism and music sheet being arranged to normally play accompaniment notes only, and other mechanism controlled by other perforations arranged and disposed in the music sheet to cause any of said accompaniment perforations or any part thereof to be switched to play solo or pedal notes within the range of the instrument.

42. In a record-controlled player action for pipe organs, a player mechanism, a tracker and a music sheet having perforations representing notes to be played on two or more registers arranged in one common group and normally controlling one register, additional perforations for causing any of the aforesaid perforations or any part of said perforations to be played on a different register whether or not the perforations representing notes to be played on the first-named register and perforations representing notes to be played on the last-named register open the tracker simultaneously.

In witness whereof I have hereunto set my hand this 4th day of January, 1926.

LEWIS B. DOMAN.
